UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

ADDING MACHINE.

1,416,364.

Specification of Letters Patent. Patented May 16, 1922.

Application filed February 2, 1920. Serial No. 355,751.

To all whom it may concern:

Be it known that I, HARRY LANDSIEDEL, a citizen of the United States, residing at Norwood, Hamilton County, and State of Ohio, have invented a new and useful Adding Machine, of which the following is a specification.

This invention relates to adding machines.

An object of the invention is to equip an adding machine with novel mechanism for indicating visually the sum or total contained or represented in the adding mechanism.

An additional object of the invention is to provide mechanism for indicating visually the sum or total contained or represented in the adding mechanism of the machine and novel controlling and actuating devices for said mechanism, said controlling 20 and actuating devices being under control of the usual adding mechanism.

With the foregoing and other objects in view, I have produced my invention in the embodiment illustrated in the drawings, in 25 which—

Fig. 1 is a side elevation of parts of the operative mechanism of a Dalton adding machine, certain of the shaft and frame parts being shown in section, and my present invention being embodied in the machine.

Fig. 2 is a plan view of a part of the operative mechanism of the machine having my present invention therein.

Fig. 3 is a broken plan of a part of the accumulating and indicating mechanism detached from the machine.

Fig. 4 is a side elevation of the same mechanism shown in Fig. 3 with the indicating 40 mechanism in its normal or idle position.

Fig. 5 is a view similar to Fig. 4 with the indicating device shown in an advanced position corresponding to the position of the adding mechanism.

Fig. 6 is a detailed view showing the device under control of the adding mechanism for actuating the indicating devices.

In order to make clear the nature and purpose of the present invention, I will first refer to the general construction of the Dalton adding machine in which, for purposes of illustration, I have shown the invention. The Dalton adding machine contains a rock shaft 1 which may be turned in one direction

by a hand lever 2, or otherwise, to permit 55 the type-carriers 3 to move toward recording position and to permit the racks 4 to move to position to operate the adding mechanism in case an item is being recorded, or to actuate the adding mechanism in clearing 60 operations. The usual differential mechanism 5 of the Dalton adding machine is shown.

The present invention comprises a pivotally supported frame for supporting the 65 adding mechanism comprising the usual adding wheels, and the indicating mechanism comprising the present invention. The pivoted frame mentioned is composed of two side members 6, a pair of plates 7 near the 70 lower side of the frame, and a tie rod 8 at the top of the frame which also constitutes the pivot upon which the frame is supported. Said rod 8 is supported in the stationary frame parts 9. 75

The adding pinions 10 are of the usual well known construction found in the Dalton adding machine and are supported for independent rotation upon a shaft 11 carried by the pivoted frame above described. The 80 adding pinions 10 are movable into and out of mesh with the actuating racks 4 by mechanism of any desired construction, one form of which mechanism is shown in Fig. 1 but not specifically claimed as a part of the 85 present invention. For present purposes, it is sufficient to know that in operating the machine to list and to add items the pivoted frame above described is automatically moved in a direction to disengage the adding pinions 10 from the actuating racks 4 prior to forward movement of the racks which accompany the type-carriers in their forward movements to positions to list the items; and to know that the pivoted frame 95 is automatically operated to move the adding pinions into engagement with the racks 4 prior to movement of said racks toward their initial or starting position. Carrying or transferring from lower to higher 100 orders is effected by the usual transfer mechanism of the Dalton adding machine, it being unnecessary to illustrate or to describe said mechanism herein. It is well known that the adding pinions in the Dalton machine and in certain other adding machines are buried within the mechanism of the machines so that it is impracticable to place

indicating dials on the same shaft with the adding pinions to indicate the sum or total contained or represented in the pinions. While the sum or total contained or represented in the adding machine may readily be ascertained at any time, without clearing the machine, simply by listing a subtotal, it is nevertheless desirable on some occasions to be informed of the sum or total in the adding pinions without the necessity of being compelled to list a subtotal. It is for the purpose of enabling the operator of the machine to know at any and all times the exact sum or total contained or represented in the adding pinions, that the present invention is provided.

A shaft 12 is supported by the side members 6 of the pivoted frame near the forward end of the frame and supports a number of independently movable dial segments 13. The dial segments 13 have type upon their peripheral edges which indicate to the operator the sum or total contained or represented in the adding pinions by being placed opposite the sight slot 14 in the case of the machine just above the key board and the sight slot 15 through the shield 16, the shield covering all of the type except the particular type which are in line with the sight slots 14 and 15. Therefore, it is impossible for the operator to become confused, since only the type which are in line with the sight slots can be seen. When the machine is clear all of the zero type on the indicators are opposite the sight slots and this condition only changes as the adding pinions corresponding to the respective indicators are operated. The indicators are operated in harmony and in accompaniment with the adding pinions to indicate accurately and immediately the sum or total contained or represented in the adding pinions. A series of pinions 17 is supported upon a shaft 18 carried by the pivoted frame. The pinions 17 mesh with the adding pinions and are rotated thereby. Each pinion 17 is equipped with a cam 19 which rises gradually from its lowest point in radial alinement with the tooth of the pinion corresponding to the zero tooth of the adding pinion to the highest point which corresponds with the nine tooth on the adding pinion. Since the zero tooth is the next one to the nine tooth there is a sudden drop from the highest point of the cam to the lowest point, as will be readily understood by reference to Fig. 6. The rise of the cam corresponds to the different values of the teeth on the pinion, so that the surface of the cam in radial alinement with the one tooth, for instance, may be said to have a value of one; and the surfaces on the cam in radial alinement with the remaining teeth have values corresponding to said teeth respectively.

Rack members 20 are operatively supported by the plates 7. The rear ends of the rack members contact with the cams 19 so that, when said cams are turned by the operation of the pinions to which they are attached, the rack members 20 are actuated forwardly in opposition to the power of springs 21 which tend to actuate the rack members rearwardly. The racks at the forward ends of the rack members mesh with 75 segmental gears or pinions 22 formed on the hubs of the indicating dials 13.

It is apparent that by the mechanism described the indicating dials will be operated coordinately with the adding pinions to bring opposite the sight slots 14 and 15 type to indicate the sum or total contained or represented in the adding pinions. When the machine is cleared, or when any adding pinions turns from any position of the value to position indicating zero the corresponding dial will be operated accordingly, due to the fact that when the highest point on the cam 19 passes the end of the rack member 20 the latter will be moved rearwardly by its spring 21, thus correspondingly moving the indicating dial.

From the foregoing it is apparent that the invention very satisfactorily accomplishes its purpose. The invention is of a simple and efficient nature and construction and does not require complete re-organization of an adding machine in order to permit use of the invention.

I do not restrict myself to unessential features but what I claim and desire to secure by Letters Patent, is:—

1. In an adding machine, adding racks, a pivoted frame, adding pinions supported in said frame and being movable into and out of mesh with said racks, cam pinions supported in said frame in mesh with said adding pinions, indicating devices in said frame for indicating the sum represented by the adding pinions, and elements operated by said cam pinions for moving said indicating devices.

2. In an adding machine, a pivoted frame, adding pinions supported in said frame, racks for operating said adding pinions, separate rack members supported in said frame, means actuated by said adding pinions for moving said separate rack members in one direction, and indicating devices operated by said separate rack members.

3. In an adding machine, a case enclosing all of the parts mentioned in this claim and having a sight opening, a swinging frame, adding pinions supported within the frame, racks supported within the frame for backward and forward movement, indicating dials supported within the frame for movement thereby adjacent to the sight opening in the case, means driven by said adding pinions for moving said racks in one direc-

- tion, independent means for moving said racks in the opposite direction, a separate series of racks supported outside of said frame for actuating said adding pinions in adding and transferring operations, and means for moving said frame to move said adding pinions into and out of engagement with said actuating racks and to move said indicating dials to position adjacent to said sight opening.
4. In an adding machine, the combination with a series of adding pinions, and a series of racks for actuating said adding pinions in adding and clearing operations, of a series of indicating dials which dials correspond to said adding pinions respectively, a shaft on which said dials are pivotally supported, a series of cam pinions meshing with said adding pinions, a shaft on which said cam pinions are revolvably mounted, cams in connection with said cam pinions respectively, racks under control of said cams, means whereby said second-named racks will actuate said indicating dials in conformity with the movements of said adding pinions to indicate the sum or total contained or represented in said adding pinions, and means for moving said dials to and from position for observation.
5. In an adding machine, the combination with a series of adding pinions, a series of racks for operating said pinions in adding and in clearing operations, and a pivoted frame for moving said adding pinions into and out of engagement with said racks, of a shaft supported in said pivoted frame parallel with the axis of said adding pinions, a series of cam pinions on said shaft meshing with and operated by said adding pinions, an additional shaft in said pivoted frame parallel with said first-named shaft, a series of indicating dials pivoted on said additional shaft, gear elements in connection with said dials respectively, racks meshing with said gear elements, and cams in connection with said cam pinions for actuating said racks in one direction.
6. In an adding machine, the combination with a series of actuating racks, a pivoted frame, a shaft supported in said frame, and a series of adding pinions mounted on said shaft and movable into and out of engagement with said racks by operation of said frame, a second shaft in said frame parallel with the first-named shaft, a series of pinions on said second shaft meshing with said adding pinions, a third shaft, indicating dials pivoted on said third shaft, and means operated in part by said second-named pinions for operating said dials to indicate the sum or total represented by said adding pinions.
7. In an adding machine, a series of adding pinions, pivoted racks for operating said pinions in adding and clearing operations,
- a shaft parallel with the axis of said adding pinions, cam pinions mounted on said shaft and meshing with said adding pinions, cams in connection with said cam pinions respectively, sliding racks separate from the pivoted racks, actuators for actuating said sliding racks in one direction into contact with said cams, a series of indicating dials operable by said sliding racks in harmony with the movement of the adding pinions to indicate the sum or total contained or represented in the adding pinions, and means for moving said adding pinions out of engagement with said pivoted racks and at the same time moving said dials to positions for observation.
8. In an adding machine, a series of adding pinions, pivoted racks for operating said pinions in adding and clearing operations, a shaft parallel with the axis of said adding pinions, cam pinions mounted on said shaft and meshing with said adding pinions, cams in connection with said cam pinions respectively, sliding racks separate from the pivoted racks, actuators for actuating said sliding racks in one direction into contact with said cams, a third shaft, a series of dials pivoted on said third shaft, and gear elements connecting said dials with said sliding racks respectively, whereby said dials will be operated by said sliding racks to indicate the sum or total represented in said adding pinions.
9. In an adding machine, a series of adding pinions, pivoted racks for operating said pinions in adding and clearing operations, supports, sliding racks mounted in said supports, a shaft parallel with the axis of said adding pinions, indicating dials pivoted on said shaft, gear elements in connection with said dials respectively engaging said racks, and mechanism actuated by said adding pinions for actuating said racks in harmony with the value positions of said adding pinions as required to cause said racks to actuate said indicating dials to positions to indicate the number or sum represented in said adding pinions.
10. In an adding machine, a series of adding pinions, a shaft parallel with the axis of said adding pinions, cam pinions on said shaft meshing with said adding pinions, cams in connection with said cam pinions respectively, supports, sliding racks carried by said supports, springs for holding said racks respectively in contact with said cams, a second shaft, gear elements on said second shaft meshing with said racks respectively, and indicating dials in connection with said gear elements respectively.
11. In an adding machine, a series of adding pinions hidden in the mechanism of the machine and being substantially invisible, a series of indicating dials supported in sight of the operator of the machine, a shaft par-

allel with the axis of the adding pinions, a series of cam pinions on said shaft meshing with and operated by the adding pinions, a cam in connection with each of said 5 cam pinions, a support, sliding racks carried by said support, springs actuating said racks into contact with said cams and arranged to yield to permit said cams to actuate said racks in one direction and arranged to move 10 said racks in the opposite directions, and operative connections between said racks respectively and said indicating dials whereby said dials are operated properly to indicate the sum or total represented in said adding 15 pinions.

12. In an adding machine, a movable frame, a shaft in said frame, adding pinions on said shaft, a second shaft in said frame parallel with the adding pinion shaft, cam 20 pinions on said second shaft meshing with the adding pinions, a cam in connection with each of said cam pinions, a support in said frame, racks carried by said support, springs holding said racks in positions for operation 25 by said cams respectively, a third shaft in said frame parallel with said other shafts, indicating dials pivoted on said third shaft, and a gear in connection with each indicating dial and meshing with the correspond- 30 ing rack.

13. In an adding machine, a case having a sight slot therethrough, a shaft, a series of indicating dials pivoted on said shaft, a movable frame for moving said dials toward and away from said sight slot, adding pinions supported in said frame, racks supported in said frame for operating said dials, mechanism operated by said adding pinions for moving said racks in one direction, and

independent means for moving said racks 40 in the opposite direction.

14. In an adding machine, a series of adding pinions, mechanism for actuating said pinions in adding and clearing operations, a shaft parallel with the axis of said pinions, 45 a series of indicating dials pivoted on said shaft, a series of sliding racks for operating said dials, means operated by said adding pinions for moving said racks in one direction, and independent means for moving said 50 racks in the opposite direction.

15. In an adding machine, adding pinions, a shaft on which said pinions are operatively supported, a second shaft parallel with said first-named shaft, cam pinions operatively supported on said second-named shaft and meshing with said adding pinions, a cam in connection with each of said cam pinions, supports, racks mounted on said supports, springs actuating said racks in one direction into contact with said cams, a third shaft, indicators pivoted on said third shaft, and gears in connection with said indicators meshing with said racks. 55 60

16. In an adding machine, a series of adding pinions, mechanism for actuating said pinions in adding and clearing operations, a shaft on which said pinions are operatively mounted, an additional shaft parallel with the adding pinion shaft, indicator dials pivoted on said additional shaft, sliding racks for operating said indicator dials, means under control of said adding pinions for controlling said dials, and a shield having a slot therein through which aligned numerals on said dials may be seen by the operator. 75

HARRY LANDSIEDEL.
